UNITED STATES PATENT OFFICE.

EDMUND P. KINNE, OF ALLIANCE, OHIO, ASSIGNOR TO AMERICAN STEEL FOUNDRIES, OF JERSEY CITY, NEW JERSEY, A CORPORATION OF NEW JERSEY.

EMERGENCY-KNUCKLE FOR CAR-COUPINGS.

No. 839,771.

Specification of Letters Patent.

Patented Dec. 25, 1906.

Application filed July 18, 1906. Serial No. 328,856.

To all whom it may concern:

Be it known that I, EDMUND P. KINNE, a citizen of the United States, residing at Alliance, in the county of Stark and State of Ohio, have invented new and useful Improvements in Emergency-Kuckles for Car-Couplings, of which the following is a specification.

My invention relates to car-couplings, and has for its object to provide an improved form of emergency-kuckle adapted to be substituted for the usual knuckle or hook in the draw-head of the type known as the "Janney" coupling, either as a substitute for a broken knuckle or hook or for use in coupling on short curves.

To this end my invention embodies certain features of construction, as will be hereinafter more definitely pointed out and claimed, reference being had to the accompanying drawings, in which—

Figure 1 is a top plan view showing to the left a coupling of the well-known Janney type in the unlocked position and to the right a Janney-type draw-head, having pivoted therein my improved emergency-kuckle in place of the ordinary knuckle or hook, the two couplings being in position for coupling. Fig. 2 is a similar view showing the couplings coupled. Fig. 3 is a perspective view of my improved emergency-kuckle. Fig. 4 is a detail side elevation of the emergency-kuckle, the same being partly broken away.

Similar numerals of reference denote corresponding parts in the several views.

In the said drawings the reference-numeral 1 indicates the usual Janney type of draw-head, to which is pivoted at 2, in place of the usual coupling-hook, my improved emergency-kuckle, the same embodying a hook portion 3 of a configuration to interlock with the usual coupling-hook 4 of the opposing draw-head 5, a front face 6 of a configuration to conform to the inner face 7 of the jaw in the opposing draw-head 5, an outside face 8 to conform to the horn 9 of the opposing draw-head 5, an elongated shank 10, which forms the point of pivotal connection with the

draw-head 1, and a recess 11 of a configuration to snugly receive the engaging end of the opposing coupling-hook 4.

Said emergency-kuckle is provided with the usual pin-receiving apertures 12 and slot 13 in its hook for use with the ordinary pin-and-link coupling and is preferably cored out quite freely, as seen in Fig. 3, a pillar or post 14 being provided at the intersection of the faces 6 and 8 to act as a buffer and to take the wear, which comes principally at this point. It is also formed with a central rib 15 along the face 8 and shank 10, in which is formed a handhold, (shown at 16 in dotted lines in Figs. 1 and 2.)

By referring to Fig. 4 it will be seen that the hole 17 in the emergency-kuckle receiving the pivot-pin 2 is slightly inclined rearward from top to bottom, which acts to prevent the emergency-kuckle from dropping excessively when used with a pin 2 that is considerably smaller than said hole 17.

From the above description it will be seen that said emergency-kuckle, while embodying practically only a hook, will substantially fill the receiving-aperture in the opposing draw-head 5, and while requiring no locking-pin or other form of locking device will not uncouple when once engaged by the hook of the opposing coupling even on the sharpest curves, this being due mainly to the fact that said emergency-kuckle is pivoted to lie outside the limits in which a Janney-type coupling-hook must be pivoted in order to disengage itself from the opposing hook when released by the locking device.

My emergency-kuckle is free to turn, but cannot turn far enough to uncouple, because its pivot-point 2 is located so far back of the hook portion 3 that even on the sharpest curves the angle between the two couplings will not be acute enough to allow said emergency-kuckle to turn sufficiently to uncouple. This operation is assisted by the fact that said emergency-kuckle is of a shape to substantially fill the receiving-aperture in the opposing Janney-type coupling, or, as it is technically known, the "Master Car-Builders' contour." Furthermore, the fact that my

emergency-knuckle is pivoted and is free to turn laterally in its draw-head makes it possible to couple with the hook 4 of an opposing coupling on the sharpest curves, which cannot be accomplished with the ordinary hooks 4 on a curve greater than about fifteen and one-half degrees.

By referring more particularly to Fig. 2 it will be observed that the pivot-pin 2 of the emergency-knuckle when the device is in coupled position is situated close to the center line of draft on the coupling, whereby I decrease the tendency of said emergency-knuckle to turn out and disengage from the knuckle 4, this location of the pivot-pin taking up some of the side motion of the coupling.

While I prefer to form my improved emergency-knuckle on lines substantially conforming to the receiving-aperture in the opposing draw-head, my invention contemplates a configuration conforming to that of the ordinary Master Car-Builders' or Janney type of coupling-hook only, such as is shown at 4, it having been found in operation that such a configuration will operate to couple under all possible conditions, the essential feature being that the emergency-knuckle proper is pivoted to move bodily laterally.

With either of the above-described constructions I am able to confine my structure to a knuckle or hook proper—that is to say, dispensing with the necessity for employing a horn similar to the horn 9 of the opposing coupling, the use of which in an emergency-

coupling renders the same more properly a 35 combined emergency-hook and draw-head.

Having thus described my invention, what I claim as new, and desire to secure by Letters Patent, is—

1. An emergency-knuckle for car-couplings embodying a hook portion, front and outside faces conjointly shaped to conform to the receiving-aperture in an opposing draw-head of the Janney type, and an elongated shank adapted to be freely pivoted to 45 its draw-head, said knuckle being cored out and having a pillar formed at the intersection of said front and outside faces to receive the wear thereon.

2. An emergency-knuckle for car-couplings embodying a hook portion only of the Master Car-Builders' or Janney type, and an elongated shank adapted to be freely pivoted in its draw-head, said parts being formed integral.

3. An emergency-knuckle for car-couplings embodying a hook portion, and an elongated shank adapted to be pivoted to a draw-head, the pivot-hole therein being inclined somewhat from the vertical.

In testimony whereof I have hereunto set my hand in the presence of two subscribing witnesses.

EDMUND P. KINNE.
